UNITED STATES PATENT OFFICE.

PAUL HENRI FLATEAU, OF PARIS, FRANCE, ASSIGNOR TO SOCIETE
UNIVERSELLE DE L'ASSERVISSEUR AUTOMATIQUE TITAN, OF
PARIS, FRANCE.

AUTOMATIC HUGGER.

No. 851,124.

Specification of Letters Patent.

Patented April 23, 1907.

Application filed August 4, 1906. Serial No. 329,227.

To all whom it may concern:

Be it known that I, PAUL HENRI FLATEAU, a citizen of the Republic of France, residing at Paris, 31 rue Le Peletier, in the Republic 5 of France, banker, have invented certain new and useful Improvements in a New Mechanical Member or Element called an "Automatic Hugger" and the Application of the said Member or Element, of which the following is a specification.

The new mechanical member termed an automatic hugger, the subject of the French Patent No. 322,017, of January 11, 1902, consists of a metal coil or helix having tapering convolutions designed to surround a drum and is closed down on the drum by means of a spring under tension in such a manner that when the helix is turned by pulling on one of its ends it closes automatically on the drum and closely hugs it and causes the drum to revolve with it.

This invention relates to an automatic hugger, which may be used on either one or two drums to prevent shocks caused by the 25 violent reversals of the handle for starting explosive engines.

Figure 1 of the accompanying drawings represents a side elevation of one embodiment of the invention; Fig. 2 represents a 30 side elevation of a modified form; Fig. 3 represents an end view of another form; and Fig. 4 represents a top plan view of a portion of the helix shown in Fig. 3.

In the form shown in Fig. 1, one part A of 35 the helix is arranged on a drum T movable around its axis t , t and the other part A' on a fixed drum T'. The end or arm C' of the part A is extended longitudinally of the drum T and is connected with the end A' of 40 the part A' by a coil spring R. When the helix is drawn in the direction of the arrow Y by means of a pull on its arm C' it will closely hug the drum T and cause it to turn with it. The friction of the convolutions of 45 the part A' on the fixed drum T' produces a retarding effect, which consists in closing the convolutions of the part A on the drum T.

If the drum T is turned in the direction of the arrow S by means of power applied 50 to the arm C' of the helix in the same direction, and should the resistance opposed to the rotation of the drum T increase so as to cause a backward turning of the drum, the

helix instead of following the drum in its rotary movement in the direction of the arrow 55 S will cease to hug the drum and permit it to turn independently thereof. At the beginning of the movement of the drum T in the direction of the arrow S, the helix will turn with it, but instead of the friction of the convolutions of part A' on the fixed drum T' being added to the action of the part A, it will counteract the same as it will be in a direction opposite to the pull of the helix and cause the helix to open and permit the drum 60 T to turn independently.

In the form shown in Fig. 2, a result similar to that described above is obtained by employing two separate members B and B' on the two drums and connecting the terminal B² of the smaller or weaker portion of the member B to the terminal B⁴ of the larger or stronger coil of the member B' by a pivot B⁵. In this form, the member B' on the fixed drum T' will not offer any material resistance 70 to the normal motion of the drum T in the direction of the arrow S', the member B' being caused to move in the direction of the arrow 75 S' by means of a pull on its larger or strong end B⁴, which is inverse to the direction in which the helix is wound. When the member B is caused to turn in the direction of the arrow S under the influence of the drum T, the member B' moves in the direction in which its convolutions are wound and closes 80 down on the drum T' and opposes in resistance having a tendency to counteract the tension of the spring R and hence releases the member B from the drum T and the drum 85 will continue its backward movement independently. The ends C³ and C⁴ of the helix shown in Fig. 2 are connected by means of the springs R and R', which are secured respectively to said ends C³ and C⁴ and to the connected arms B² and B⁴.

In the modification shown in Figs. 3, 4, the helix is made in the form of a chain composed of links e, e', e², e³, e⁴, etc., which fit around the drum T and vary in number and thickness from one end to the other of the 90 chain according to the resistance desired at the several points of the helix. This form is designed to be used in apparatus which requires a certain amount of precision and a great deal of sensitiveness. The chain being 95 articulated is more flexible than the coiled

rod and will fit very exactly on the drum and under a very slight tension of the spring R and this articulated helix may be applied in the same manner as that shown in Figs. 1 or 2.

5 The above described embodiments in which two drums are used, one of which is fixed and the other movable, may be employed in all cases where the helix is used for carrying forward another member and where it is desired to avoid accidents arising from an untimely reversal of the drive caused by either an increase in resistance or by a decrease in the drive.

15 I claim as my invention:

1. The combination of a fixed drum, a movable drum, a helix wound partly on one drum and partly on the other, and spring means for connecting the ends of said helix.

2. The combination of a fixed drum, a movable drum, a helix formed of a plurality of members connected together, and spring means connecting its opposite ends.

3. The combination of a fixed drum, a movable drum, a helix composed of two coiled members, one wound on one drum and one on

the other, the weak end of one coil being connected with the strong end of the other and spring means connecting the free ends of said coils.

30

4. The combination of a fixed drum, a movable drum, a helix composed of two coiled members, one wound in one direction on one drum and the other wound in the other direction on the other drum, the weak end of one coil being connected with the strong end of the other, and spring means connecting the free ends of said coils.

35

5. The combination of a fixed drum, a movable drum, a helix adapted to be wound partly on one drum and partly on the other and composed of connected members and spring means for connecting the ends of said helix.

40

In testimony, that I claim the foregoing as 45 my invention, I have signed my name in presence of two subscribing witnesses.

PAUL HENRI FLATEAU.
